UNITED STATES PATENT OFFICE.

JOHN W. PUTERBAUGH, OF CLARINDA, IOWA.

FENCE-MACHINE.

SPECIFICATION forming part of Letters Patent No. 417,279, dated December 17, 1889.

Application filed August 29, 1889. Serial No. 322,305. (No model.)

To all whom it may concern:

Be it known that I, JOHN W. PUTERBAUGH, a citizen of the United States, residing at Clarinda, in the county of Page and State of Iowa, have invented a new and useful Fence-Machine, of which the following is a specification.

This invention relates to machines for manufacturing that class of fences which are constructed of wire and wooden slats interwoven; and it has for its object to construct a machine of this class in which the necessity of inserting the slats or pickets endwise into the bights of the wires shall be dispensed with.

The invention consists in the improved construction, arrangement, and combination of parts which will be hereinafter fully described, and particularly pointed out in the claims.

In the drawings hereto annexed, Figure 1 is a perspective view of my improved fence-making machine. Fig. 2 is a longitudinal vertical view of the same. Fig. 3 is a top view. Fig. 4 is a longitudinal sectional view of a part of the machine, showing the devices for forcing the pickets down into the bights of the wires in operative position. Fig. 5 is a vertical transverse sectional view taken on the line $x-x$ in Fig. 3. Fig. 6 is a perspective detail view of one of the twisting-heads detached from the machine. Fig. 7 is a detail view.

Like numerals of reference indicate like parts in all the figures.

1 designates a bench or table, which is mounted upon a frame 2, supported upon legs 3. The table 1 is provided with a vertical transverse slot 4, the front and rear sides of which have vertical segmental recesses 5, affording bearings for the twisting-heads. The latter consist of segmental stems or shanks 6, provided at their upper and lower ends with segmental heads or flanges 7 and 8, the former of which are provided along their peripheries with radially-extending teeth or sprockets 9, and the under sides of the said upper flanges 7 are provided with segmental grooves 10, adapted to engage segmental flanges 11, formed upon the upper side of the bench or table adjacent to the recesses 5. The flanges 8, at the lower ends of the shanks

6 of the twisting-heads, are adapted to bear against the under side of the bench or table. It will be seen by this construction the twisting-heads are retained securely in operative position, the flanges 11 engaging the grooves 10, and the flanges 8 combining to prevent the said twisting-heads from being dislodged. The twisting-heads in the oppositely-located recesses 5 are arranged concentrically, and are separated only by the longitudinal slot 4. It follows that the said twisting-heads may be rotated in the bearings formed by the segmental concentric recesses 5 by means of a suitable mechanism, which will be presently more fully described.

The twistlers have been described in the foregoing as being "segmental," and it should be added that they are to be less than full semicircular, since the segmental and less than semicircular twistlers leave an opening as broad as the slot 4 in the table, through which a picket may drop, as will be herein-after described, whereas semicircular twistlers would have to be separated by other means before they would allow a picket to drop through.

The heads 7 at the upper ends of the twistlers are provided with upwardly-extending lugs or brackets 12, forming bearings for the spools 13, upon which is wound the wire 14, which is to be used in the manufacture of the fence. Each of the twistlers is provided with a vertical perforation 15, through which the wire 14 is threaded.

16 designates a guide-roller, which is journaled in brackets 17, depending from the sides of the frame. At the rear end of the frame are provided bearings for a transverse roller 18, upon which the fence is wound as it is being delivered from the machine. One of the side beams of the frame is provided on its inner side with a bracket 19, which, together with the adjacent frame-beam, affords bearings for a short shaft 20, (shown in Fig. 7 of the drawings,) upon which is secured a ratchet-wheel 21.

22 designates a pawl attached to the frame and engaging the ratchet-wheel to prevent reverse movement of the latter.

23 is an oscillating frame mounted pivotally upon the shaft 20, astride the ratchet-wheel 21, and having at its upper end a piv-

oted pawl 24, engaging the said ratchet-wheel. The lower end of the frame 23 is connected by a link or connecting-rod 25 with an arm or crank 26, extending from one end of a rock-shaft 27, which is journaled transversely at one end of the frame. The opposite end of the rock-shaft 27 has a crank or handle 28, by means of which it may be manipulated. It will be seen that by operating the rock-shaft 27 an intermittent rotary motion may be imparted to the shaft 20. The latter is provided at its outer end which projects beyond the bracket 19 with a square post or projection 29, adapted to enter a correspondingly-shaped recess 30 in the end of the roller 18. The opposite end of the latter has a pin-tle 31, adapted to be journaled in a bearing provided for its reception in one of the side pieces of the supporting-frame. The roller 18, as will be seen, may thus be connected detachably with its operating mechanism. The said roller is provided with transverse slots 32, in which tongues 33 are pivotally mounted. These tongues may be adjusted to a position transverse to the shaft, when they will serve to engage the pickets at the end of the fence and hold the latter from slipping as it is being wound upon the said receiving-roller.

30 The bench or table of the machine is provided near one end with bearings for a vertical shaft 34, carrying at its upper end a sprocket-wheel 35 and at its lower end a pinion 36, which meshes with the pinion 37 upon a counter-shaft 38. The latter extends through the front side of the frame, and carries at its front end a crank-wheel 39, by means of which it may be operated.

40 designates a chain running over the sprocket-wheel 35 and engaging the teeth or sprockets 9 at the peripheries of the flanges at the upper ends of the twisters, of which latter five pairs are usually to be employed, although in the drawings hereto annexed only three pairs have been shown. At the end of the bench or table opposite to the sprocket-wheel 35 is journaled a guide-wheel or pulley 41 for the opposite end of the chain 40.

50 Idlers or friction-wheels 42 are mounted upon the bench of the machine to bear against the sides of the sprocket-chain intermediately between the several sets or pairs of twisters. It will be seen that by this mechanism rotary movement may be imparted simultaneously to the several sets of twisters, the result being to twist the previously-connected ends of the wires extending downwardly from said twisters.

60 A series of guide-rods 44 are arranged vertically on opposite sides of the vertical slot 4, the purpose of said rods being to guide the pickets used in the manufacture of the fence into the said slot. One end of the slot 4 has a vertical gage-bar 45, and the opposite end 65 of the said slot is provided with a spring 46, attached at the upper end of said slot and serving to force the ends of the pickets against

the gage-bar as they are being fed into the machine, thereby securing uniformity in the position of the pickets with relation to the 70 wires.

To the under side of the bench 1 adjacent to the front side of slot 4 is journaled a rock-shaft 47, having arms 48, adapted to work in recesses 49, formed in the under side of the 75 bench and communicating with the slot 4. By oscillating the rock-shaft 47 in its bearings the arms 48 may be thrown in a forward direction across the slot 4. The arms 48 are normally held in an upright position by the 80 action of a spring 50 coiled upon the said rock-shaft. The latter is provided with a downwardly-extending arm 51, to which is attached one end of an operating cord or chain 52, which passes over a guide-pulley 85 53, and the other end of which is attached to a treadle 54, which is hinged to a bracket 55, depending from the front side of the frame of the machine.

To the under side of the bench in rear of 90 the slot 4 is attached a series of guide-brackets 56, to prevent forward movement of the picket, which is being engaged and operated upon by the arms 48 of the rock-shaft 47.

In operation the ends of the wires, which 95 are threaded through each pair of twisters, are first connected by twisting the same across the slot 4 directly at the lower ends of the twisters. A slat or picket is then dropped through the slot 4 until it rests upon the 100 wires, when, by operating the rock-shaft 47 by means of the treadle 51, the said picket will be forced the required distance in a downward direction. By operating the crank-wheel 39 a rotary movement is now imparted 105 to the sprocket-wheel 35, causing the chain 40 to rotate the several sets of twisters in their respective bearings, and thus twisting the wires above the slat or picket which has been inserted in the machine. The wires may 110 be given one or more twists, as may be desired, and the twisters will be stopped at a point where their inner straight sides shall be in alignment with the sides of the slot 4. Another picket is then inserted and the operation is repeated until a sufficient length 115 of fence has been made to enable it to be passed under the guide-roller 16 and attached to the winding-roller 18. The latter may then be intermittently operated for the purpose of 120 winding the fence until a roll of the desired size has been formed, when the operation may be temporarily suspended while the said roll is being removed.

The pickets from which the fence is being 125 manufactured may be supported upon the frame of the machine in rear of the bench or table, or upon a shelf above the table, where they may be conveniently reached by the operator.

130 My improved machine, as will be seen from the foregoing description, is very simple in its construction, and it may be manufactured at a moderate expense. To operate the ma-

chine rapidly and successfully, the services of but one man are required.

Having thus described my invention, I claim and desire to secure by Letters Patent of the 5 United States—

1. In a fence-machine, the combination, with a horizontal bench or table having a vertical transverse slot provided on opposite sides with segmental concentric recesses, of 10 the revoluble segmental twisters journaled in said recesses on opposite sides of the slot, means for retaining the said twisters in their bearings, and mechanism for imparting rotary movement to the said twisters, substantially as and for the purpose herein set forth. 15
  2. In a fence-making machine, the combination of a bench having a vertical transverse slot provided with segmental concentric recesses and segmental flanges at the upper ends of said 20 recesses, with the segmental twisters mounted revolubly in the said recesses and provided at their upper ends with heads or flanges, the under sides of which are provided with segmental grooves to engage the flanges at 25 the upper ends of the segmental recesses, substantially as and for the purpose herein set forth. 30
  3. In a fence-making machine, the combination, with a bench having a vertical transverse slot provided on opposite sides with segmental concentric recesses, of the twisters consisting of the segmental shanks provided at their upper and lower ends with segmental heads or flanges adapted to bear against the 35 upper and under sides of the bench, substantially as herein set forth. 40
  4. In a fence-making machine, the combination, with a bench or table having a vertical transverse slot provided on opposite sides with segmental concentric recesses, of the segmental twisters mounted revolubly in said 45 recesses and provided at their upper ends with segmental flanges having radially-extending teeth or sprockets, substantially as and for the purpose set forth. 50
  5. In a fence-making machine, the herein-described twisters comprising the segmental shanks provided at their upper and lower ends with segmental flanges and having vertical perforations, said upper flanges being provided with radially-extending teeth or sprockets, and with segmental grooves in their under sides, substantially as and for the purpose set forth. 55
  6. In a fence-making machine, the combination of a bench or table having a vertical slot provided on opposite sides with segmental concentric recesses, the segmental twisters mounted revolubly in the said recesses and having vertical perforations, the brackets extending upwardly from the upper ends of said twisters, and the wire-spools mounted in the said brackets, substantially as and for the purpose set forth. 60
  7. In a fence-making machine, the combination of a bench or table having a vertical transverse slot provided with segmental 65
- centric recesses and segmental flanges at the upper edges of the same, the segmental twisters mounted revolubly in said recesses 70 and provided at their upper ends with segmental flanges having segmental grooves in their under sides to engage the flanges at the upper ends of the bearings and having radially-extending teeth or sprockets, the wire-spools mounted upon the upper ends of the twisters, a chain arranged to engage the sprocket-flanges of the twisters, a sprocket-wheel and a guide-pulley to support the said chain, and suitable operating mechanism, 80 substantially as and for the purpose herein set forth. 85
8. The combination of a bench or table having a vertical transverse slot provided with concentric recesses on opposite sides, the 90 twisters mounted revolubly in the said recesses, a guide-bar secured vertically at one end of the slot, and an inwardly-extending spring secured at the upper edge of the opposite end of the slot, substantially as and for the purpose set forth. 95
9. The combination of a bench or table having a vertical transverse slot provided with segmental concentric recesses on opposite sides, the twisters mounted revolubly in the 100 said recesses, a rock-shaft journaled to the under side of the bench adjacent to the front side of the slot and having upwardly-extending radial arms working in recesses in the bench, communicating with the slot, a treadle and connecting mechanism to operate the said rock-shaft, and a spring coiled upon the latter to hold the radial arms normally in an upright position, substantially as and for the purpose set forth. 105
10. In a fence-making machine, the combination of the vertically-slotted bench, the segmental twisters mounted revolubly in recesses or bearings on opposite sides of the said slot and carrying the wire-spools at their 110 upper ends, the rock-shaft having radial arms journaled at the lower front edge of the slot, and the guide-brackets secured to the under side of the bench adjacent to the rear edge of the slot, substantially as herein set forth. 115
11. The combination of the vertically-slotted bench, the segmental twisters mounted revolubly in recesses or bearings on opposite sides of said slot, the guide-rods mounted vertically on opposite sides of the slot upon 120 the upper side of the bench, the vertical gage-bar secured at one end of the slot, and an inwardly-extending spring secured at the upper edge of the opposite end of the slot, substantially as set forth. 125
12. In a fence-machine, the combination of the supporting-frame, the vertically-slotted bench, the segmental vertical perforated twisters mounted revolubly in recesses or bearings on opposite sides of the slot and carrying 130 the wire-spools at their upper ends, mechanism for imparting rotary motion simultaneously to the several sets of twisters, a rock-shaft journaled to the under side of the bench

adjacent to the front edge of the slot and having radially-extending arms, a guide - roller journaled in brackets depending from the frame of the machine, a winding-roller mounted detachably in bearings at the rear end of the frame, and mechanism for imparting intermittent rotary motion to the said winding-roller, substantially as and for the purpose set forth.

In testimony that I claim the foregoing as to my own I have hereto affixed my signature in presence of two witnesses.

JOHN W. PUTERBAUGH.
